UNITED STATES PATENT OFFICE.

GABRIEL GOMAND, OF BARCELONA, SPAIN.

BALANCED SLUICE VALVE.

Application filed March 18, 1924. Serial No. 700,161.

To all whom it may concern:

Be it known that I, GABRIEL GOMAND, a citizen of the Republic of France, residing at Barcelona, Spain, have invented certain new and useful Improvements in Balanced Sluice Valves, of which the following is a specification.

This invention has for its object to provide a balanced sluice valve in which the effects of the pressure are fully eliminated, and balance automatically obtained, without the intervention of any mechanical means, and which is not liable to get out of balance even should the valve remain unsupported or become damaged.

The invention relates primarily to sluice valves of the type disclosed in my prior French Patent No. 523,476, issued April 22, 1921, but essentially involves certain developments of, and improvements on, the earlier construction; the purpose being to provide an improved device which is specially designed for use where very high current speeds are involved, and which is so constructed as to practically eliminate load losses despite such speeds. The present case, wherein the invention is fully disclosed, is a continuation in part of my co-pending application No. 570,981, filed June 26, 1922, now Patent No. 1,507,280, granted September 2, 1924.

According to my present invention, and to effect the object stated above, I utilize, in place of the fixed partition or guide member R of the construction shown in the aforesaid French patent, a movable part or member which can be opened or closed in correspondence with the respective movements of the valve so that it may be regarded, in a sense, as forming a second or auxiliary valve. In the construction according to the French patent, the part R referred to serves merely to guide the incoming upstream current of liquid or fluid to the two feed channels leading toward the outlet; and as said part is fixed, communication between the inlet and outlet is accomplished solely by way of the above-mentioned channels and, hence, is necessarily indirect. With the movable part or auxiliary valve of the present case, however, the movement thereof into open position permits the current to flow immediately from the inlet to the outlet or, in other words, provides a direct communication therebetween. This direct passage of the current from inlet to outlet without

change of direction has the effect of avoiding shock and consequent load losses; and even if some of the current still continues to flow through the channels to the outlet, still the main body of the current will necessarily follow the direct path, and the slight complementary loss occasioned by the flow through the channels will serve to reduce the speed and, therefore, the load losses in the valve.

In the accompanying drawings:

Figure 1 is a central vertical sectional view of the complete invention;

Fig. 2 is a similar section taken at right angles to Fig. 1, on line 2-2, Fig. 3;

Fig. 3 is a horizontal section on line 3-3, Fig. 1;

Fig. 4 is a central vertical section of a modification; and

Fig. 5 is a horizontal section on line 5-5, Fig. 4.

Referring more particularly to Figs. 1 and 3, the construction therein illustrated comprises a metallic casing A fitted with two flanges which, however, may obviously be replaced by various other fastening means. The upper portion of the casing is provided with a hemispherical cap G; and at the center of the casing there is disposed the valve B which, in its closed position, is subjected to pressure on two opposite sides through the channels C and D bored in the casing, said channels having any suitable cross-sectional shape. The surfaces of the valve in contact with the casing are provided with bronze facings or liners F for coaction with seats or bearings E on the casing (Fig. 2) in order to prevent oxidation, which would interfere with the necessary tightness, and to facilitate repairs.

The valve B is mounted on an operating rod H having a screw-threaded portion I which extends through and coacts with the threaded wall of a hole formed vertically in a nut M that is inserted through and locked in a horizontal, transverse recess in the upper part of the valve; and the latter is itself provided along its inner vertical face with a pair of spaced, longitudinal guide ribs X (Fig. 3) which receive between them a vertical tongue V. The upper portion of the rod projects through a stuffing box J at the top of the casing fitted with a cap K and suitable packing L, and ends in a squared part U to facilitate its rotation, and the lower portion of the rod projects through

a similar stuffing box on the bottom of the casing.

Due to the arrangement above described, it will be apparent that rotation of the operating rod in the proper direction will cause the valve to move upwardly from its fully-closed position to its fully-open position, the speed of such movement depending upon the pitch of the threads on the rod 10 as well as on the angular speed at which the hand wheel, key or other manipulating device on the squared end of the rod is turned. In the closed position of the valve, the bronze-to-bronze contact of the bearings 15 E, F insures tightness. The rod itself, however, is held against endwise movement during its rotation by means of a stop N which fits in a seat of the same depth as the height or thickness of the stop formed 20 in the top of the cap G and closed by the bottom member of the stuffing box J. The combined weight of the valve and rod is exactly equal to the upward reaction or force exerted upon the valve by the pressure within the casing, as previously stated, less the deduction for displacement of the valve and the submerged portion of the rod; it being assumed that a known pressure is involved and that the weight is 25 calculated accordingly.

The structure thus far described is generally similar to that disclosed in my above-identified prior French patent; and such resemblance is augmented by the fact that 30 the part or member R forms an abutment or guide against which the in-coming current from up-stream impinges, and by which it is directed into the two channels C and D, as indicated by the arrows g and h (Fig. 3). In the construction according 35 to said French patent, however, the part R is integral with the casing and, hence, is permanently fixed in position, so that it completely precludes any direct or straight-line passage of the current from the inlet P to the outlet T but, on the contrary, compels the current to pass into and through 40 the curved channels irrespective of the position of valve B.

On the other hand, the part R in the present construction, on the back of which, incidentally, the guide tongue V is formed, is movable instead of stationary, so that it can be raised or lowered at will and, hence, 45 acts in a way as an auxiliary valve. Consequently, when both valves B and R are raised, a direct passage is left open from inlet to outlet, and the current will, therefore, be free to flow straight through such 50 passage, though as a matter of fact some small part of the current may still flow through the channels C and D. Bronze bearings E' and F' are provided at the contacting edges of the valve R and the 55 adjacent portions of the casing for the rea-

sons explained above in connection with the bearings E and F; and a vertical space or chamber S is left between the parts R and B, which chamber communicates at its lower end with a relatively-shallow space 70 or chamber S' left between the bottom of the main valve B and the bottom of the casing, said chamber S' opening into the outlet T. The purpose of the chambers S and S' is to permit foreign substances to 75 collect in the latter chamber without obstructing the operation of the device, such substances thereafter being drained out by the current when the valves are opened.

To effect the vertical movements of the 80 auxiliary valve R incidental to its opening and closing, mechanism substantially similar to that employed to operate the main valve B may be utilized, and the two valves may, if desired, be connected in some 85 suitable manner to work conjointly or in unison. It is advisable, however, to open the main valve first and then the auxiliary valve, which can be readily done since the latter valve is balanced by the up-stream 90 and down-stream pressures, and, conversely, to close the auxiliary valve ahead of the main valve in order to take advantage of the same balance. This restores the balance 95 of the main valve, which can then be readily lowered into closed position.

In the construction herein illustrated, the valve R is slidably mounted on a second operating rod H' and may be equipped with a locked nut M' in engagement with the 100 threaded portion I' of the rod, the opposite ends of which latter project through upper and lower stuffing-boxes J'. The upper end of the rod may terminate in a squared portion U' for engagement by a hand-wheel, 105 key or the like. The direct engagement of the coacting guides X and V on the two valves insures their movements in proper relation to each other by preventing lateral displacements thereof.

While the auxiliary valve preferably has the shape above described, it may, of course, take various other forms; for instance, that of a butterfly valve or throttle, as represented at R' in Fig. 5. This valve R' will be rocked, however, about the vertical axis of its rod H' instead of being raised or lowered, and it will coact with two vertical walls or partitions A' disposed in spaced, 110 parallel relation within the casing and formed integral therewith. When moved to a position midway between and parallel with said walls, it will open a direct passage from inlet to outlet, as before.

I claim as my invention:—

1. A balanced sluice valve, comprising a casing provided with an inlet and an outlet for the current, a pair of oppositely-located channels within the casing leading from the inlet toward the outlet, a vertically movable 120

valve in the casing for controlling communication between said channels and outlet, a movable member located in the casing immediately opposite the inlet to normally 5 direct the in-coming current into said channels, and operating means for opening and closing the valve and the movable member; said movable member and valve, when both are in open position, opening a direct, 10 straight-line passage for the current from inlet to outlet; substantially as described.

2. A balanced sluice valve, comprising a casing having an inlet and an outlet for the current; a pair of oppositely-located 15 channels within the casing leading from the inlet toward the outlet; a guide member located in the casing immediately opposite the inlet for directing the in-coming current into the channels; a valve for controlling 20 communication between the delivery ends of the channels and the outlet; operating means for the valve; and means for moving said guide member into open position to provide a direct, straight-line passage for the current from inlet to outlet when said valve 25 is open.

3. A balanced sluice valve, according to

claim 2, in which both the valve and the guide member are mounted for vertical movement within the casing; substantially as 30 described.

4. A balanced sluice valve, comprising a casing having an inlet and an outlet for the current, a balanced main valve in the casing for opening and closing an indirect passage for the current from inlet to outlet, a balanced auxiliary valve in said casing for opening a direct, straight-line passage for the current from inlet to outlet when the main valve is open, and operating means 40 for the valves; substantially as described.

5. A balanced sluice valve, comprising a casing having an inlet and an outlet for the current, a vertically movable main valve in the casing for opening and closing an indirect passage for the current from inlet to outlet, a vertically movable auxiliary valve in said casing for opening and closing a direct, straight-line passage for the current from inlet to outlet when the main valve is 45 open, and means for raising and lowering the valves; substantially as described.

In testimony whereof, I affix my signature.

GABRIEL GOMAND.
